UNITED STATES PATENT OFFICE.

ARTHUR W. BARNARD, OF NEWTON CENTER, MASSACHUSETTS.

CHUTE CONSTRUCTION FOR COIN-CONTROLLED MACHINES.

Application filed May 17, 1922. Serial No. 561,758.

To all whom it may concern:

Be it known that I, ARTHUR W. BARNARD, a citizen of the United States, and a resident of Newton Center, in the county of 5 Middlesex and State of Massachusetts, have invented certain new and useful Improvements in Chute Construction for Coin-Controlled Machines; and I do hereby declare the following to be a full, clear, and exact 10 description of the invention, such as will enable others skilled in the art to which it appertains to make and use the same.

This invention relates to improvements in coin-controlled machines and more particularly to means for controlling the passage of 15 a coin whereby some of the coins will be conducted to a receptacle within the casing of the machine and other coins returned to a patron,—my improvements being intended 20 for use with coin-controlled means for scales, but may be employed with other machines in which a controlling part is operated by a coin deposited into the machine.

With coin return devices as heretofore 25 constructed, considerable loss to patrons has occurred by reason of the placing of a barrier, such as a wad of paper, in the coin outlet just above the coin return cup and out of sight of the patron, which barrier would 30 operate to cause an accumulation of returned coins just above the cup instead of being delivered to the patrons. The accumulated coins could afterwards be obtained by an unauthorized person by simply removing 35 the wad or barrier and thus rob patrons of coins which they should have received.

An object of my invention is to obviate 40 the above mentioned defect of return coin devices as heretofore constructed and to provide a coin passage in which the coin can be viewed by the patron from the time that it enters a visible chute until it has either been discharged into a coin receptacle within the casing of the machine or returned to the 45 patron, and thus prevent the employment of a wad or barrier which could without the presence of such barrier being denoted to the patron.

With this and other objects in view, the 50 invention consists in certain novel features of construction and combinations of parts as hereinafter described and pointed out in the claims.

In the accompanying drawings, Figure 1 55 is a view in front elevation of a coin chute

construction and coin return means embodying my improvements. Figure 2 is a longitudinal sectional view on the line 2—2 of Figure 1, and Figure 3 is a transverse sectional view on the line 3—3 of Figure 1. 60

My improved chute construction may be mounted in any suitable manner in the front wall of the casing of a coin controlled machine, such as scales for example, and it comprises a plate 1 provided at its side edges 65 with longitudinal bars or frame members 2 having grooves 3 in their inner portions to receive the side edge portions of a glass front plate 3^a,—said grooves being so located that the glass front will be properly spaced from the back plate 1 to permit the free passage of a coin through the chute formed by these parts. The back plate 1 is provided with numerous pins 4 which extend across the chute to the glass front and cause the coin 70 to travel in a circuitous route through the chute. My improved coin chute is appreciably greater in width than coin chutes commonly employed and it is provided near its lower end and centrally between its side 75 edges with a coin return device. This device may be termed a "coin return cup" and it may consist of a tubular portion 5 which is passed through a suitable hole in the glass front plate and of sufficient length to extend 80 to the back plate 1,—said tubular portion having a circular flange disposed against the outer face of the glass front and may be cemented or otherwise secured thereto. That portion of the tubular part of the coin return cup which extends across the chute 85 space is provided in its upper portion with a slot 6 which communicates with the lower portion of said chute space and is sufficient in size to permit the passage into said cup 90 of a coin.

After a coin shall have passed the device 95 in the machine which it has operated, it will fall directly into the upper end of my improved chute and travel downwardly 100 through the same until it reaches the lower end portion, from which it may escape by passing through the open lower end of the chute and be directed by any suitable means to a coin receptacle within the casing of the machine. Some of the coins may so travel 105 through the chute that they will fall into the coin return cup. It is evident that by locating the coin return cup with respect to the glass front of the chute as above de- 110

scribed, it will be impossible to choke the coin cup with an invisible barrier which might, in other constructions, cause an accumulation of coins invisible to the patron, and furthermore should such choking of the coin cup be attempted, the patron could easily see through the glass front whether any coin would fall upon such barrier and be permitted to escape through the coin receptacle within the casing of the machine.

Having fully described my invention what I claim as new and desire to secure by Letters-Patent is:

1. A coin chute for coin-controlled machines having a transparent front extending to the lower terminal of the chute, and a tubular coin return member inserted through the transparent front above the lower end

thereof whereby an obstruction in said coin return member will be visible at the front. 20

2. A coin chute for coin-controlled machines having a transparent front extending to the lower terminal of the chute, and a straight tubular coin return member inserted axially through the transparent front above the lower end thereof whereby an obstruction in the coin return member will be visible at the front of the chute, the rear end of the coin-return member abutting the back of the chute and there being a coin-receiving opening in the top of the member between the front and back of the chute. 25 30

In testimony whereof, I have signed this specification.

ARTHUR W. BARNARD.
